UNITED STATES PATENT OFFICE.

FRANK BARTOS, OF HELENA, MONTANA, ASSIGNOR OF ONE-HALF TO SHIRLEY C. ASHBY, JR., OF HELENA, MONTANA.

LANDING NET.

1,416,543.

Specification of Letters Patent. Patented May 16, 1922.

Application filed October 7, 1920. Serial No. 415,436.

To all whom it may concern:

Be it known that I, FRANK BARTOS, a citizen of the United States, residing at Helena, in the county of Lewis and Clark and State 5 of Montana, have invented certain new and useful Improvements in Landing Nets, of which the following is a specification.

This invention relates to nets and more particularly to that class of such devices 10 known as landing nets, and has for its primary object the provision of a landing net of the character set forth which is adapted to be reduced in area in order that the same may be placed within the pocket of the user 15 or packed away without the usual inconvenience of transporting such articles.

With the foregoing and other objects in view as will from time to time hereinafter appear this invention consists in the peculiar 20 arrangement and combination of the various parts of a landing net as hereinafter described and more particularly pointed out in the added claims.

Referring to the accompanying drawings 25 forming a portion of this specification and in which the same reference numerals indicate the same parts wherever used,

Figure 1 is a side elevation, partly in section and partly broken away, and showing 30 the handle in its extended and retracted position;

Fig. 2 is a front elevation partly in section and partly broken away, and

Fig. 3 is a section on line 3, 3 of Fig. 1. 35 The net 4 is supported in the usual manner upon the net hoop 5 shown broken away for clearness of illustration.

The net hoop 5 terminates in a pair of arms 6 and 7 extending from bends 8 and 40 9 respectively and terminating in screw-threaded ends 10.

A casting designated as a whole by the 45 numeral 11 and formed of suitable material is provided with ears 12 and 13 centrally bored out at 14 to receive respectively the members 6 and 7 which pass therethrough and are held in position therein by means of binding nuts 15 engaging the threaded ends 10.

50 The casting 11 is further provided with a central bore 16 tapered from the inner end 17 thereof to a reduced diameter at the outer end 18 and is adapted to receive a

handle 19 having a shank 20 reversely tapered to the taper of the bore and which 55 forms with the bore 16 a jam fit when the members are in the position shown in full lines in Fig. 1, and when the parts are in such position the net is adapted for use.

When it is desired to reduce the net to 60 a small compass in order to insert the same in the pocket or to pack the net away, the handle 19 is moved from the position shown in full lines in Fig. 1 to position shown in dotted lines therein until the handle is in 65 such position that it is within the area of the net hoop, thus providing a compact article which may be easily carried wherever desired.

By the construction as above described 70 there is provided a landing net which may be carried in the pocket and be readily secured and put into operative or unfolded position with one hand by grasping the 75 handle and withdrawing the net from the pocket, whereupon the net may be unfolded by a downward fling of the hand which causes the net to slide along the handle to its unfolded position.

What I claim is:

1. In a net in combination with a net hoop, a casting carrying said hoop and provided with a tapered bore, and a handle reversely tapered to the taper of the bore of the casting and adapted for sliding engagement therewith whereby the forward end of the handle is adapted to be moved within the area of the net hoop when it is desired to reduce the device to smaller compass. 80

2. In a net in combination with a net hoop, a casting having a tapered bore, a pair of ears formed on said casting, said ears having engaging means for the terminal ends of said hoop, means for removably securing said hoop ends to said ears, and a handle correspondingly tapered to the casting bore to removably engage the same. 85

In testimony whereof I affix my signature 90 in the presence of two witnesses.

FRANK BARTOS.

Witnesses:
